UNITED STATES PATENT OFFICE.

FREDERICK ROTTI, OF ELIZABETHPORT, NEW JERSEY.

WINDOW-STAND.

1,218,321.

Specification of Letters Patent.

Patented Mar. 6, 1917.

Application filed May 28, 1915, Serial No. 30,999. Renewed December 5, 1916. Serial No. 135,270.

To all whom it may concern:

Be it known that, I, FREDERICK ROTTI, a citizen of the United States, residing at Elizabethport, county of Union, and State of New Jersey, have invented certain new and useful Improvements in Window-Stands, of which the following is a specification, reference being had to the accompanying drawings.

- 10 This invention relates to certain improvements in window stands which are adapted to be used by painters, house decorators, window washers and others and has for its object the provision of a structure wherein 15 the main working surface is continuous from end to end and also the stand is provided with steps by which the desired working position of the operator may be attained.

Heretofore window stands have had several objections; by providing a solid top working surface they did not enable the operator to assume a higher or lower position on the stand so that the various parts of the window could be reached in his best 25 possible working condition, or by providing steps above or below the main surface a portion of said surface had to be removed and thereby endangering the life of the operator who was liable through absent-mindedness to step into the hole.

In this invention the above difficulty is obviated by providing steps to either side of the main working surface and therefore the said surface may be made continuous from 35 end to end.

In the accompanying drawings; Figure 1 is a side elevation of the stand as applied to a window; Fig. 2 is a bottom plan view of the stand; Fig. 3 is a section on line 3—3, 40 Fig. 2; and Fig. 4 illustrates a modification of the stand as applied to a window balcony.

Similar letters of reference indicate like parts throughout the accompanying specification.

45 Referring more particularly to the drawings, 5 indicates a main working surface comprising a board which is solid from end to end, the inner end of this board is adapted to rest on the window sill, and adjacent the 50 outer end on each side thereof are arranged two inwardly inclined depending supports 6 and 6' which rest against the wall below the window opening. The supports 6—6' may be braced by crossed strip members 7 and 7' 55 if desired and thereby give the construction more solid condition. Attached intermediate

the ends of the working surface 5 and in vertical respect thereto are strut members 8 and 8' which are secured at their lower ends to the inclined supports 6 and 6'. 60

Strips 9, 10, 11 and 12 are arranged transversely and secured to the members 6—6' and 8—8' and they extend slightly beyond said members and the board 5 to form supports for steps 13, 13', 14 and 15. In addition to the fastening of the strip 12 by means of nails or the like clips 16 and 16' are arranged to embrace the same as a safe guard against displacement. 65

Adjacent the lower ends of the supports 6 and 6' are apertures 17 and 17' arranged to receive a rod 18 which extends beyond the sides of the supports. By this construction the support will be maintained in its proper position by the rod engaging the 75 wall should there be an opening directly below the window.

Arranged adjacent the sides and the inner end of the main working surface 5 are longitudinal slots 19 and 19'. On the under 80 side of the board and transversely thereof is a securing member 20 provided on one of its faces with a notched portion 21, which is adapted to fit snugly the projecting portion of the sill, but should the sill be too 85 thick or thin the opposite side of the member is used. This side is provided with a plurality of biting teeth 22 which are adapted to embed themselves into the woodwork. For securely holding the securing member 90 20 in its adjusted position the bolt members 23 and 23' are employed, these in turn are fastened by winged nuts 24 and 24'. The cross strip 5' is added to the outer end of the board 5 simply to strengthen the latter. 95

In order that the operator may attain a higher working surface than that presented from the main working surface a stand 25 may be secured to the upper surface of 5 by bolt and nut members 26—26' and 100 27—27' respectively.

In the modified form as illustrated in Fig. 4 wherein is shown a balcony there may be employed a plurality of window supports over which a board 28 may be placed and secured in position by a bolt and nut members 29 and 29'. A railing or guard may also be provided and secured in any efficient manner to the board 28 if desired. 105

While I have described in the foregoing 110 specification the preferred embodiment of my invention, I wish it to be understood that

I may change the specific arrangement of the parts without in any way departing from the spirit and scope of my invention.

What I claim is:

- 5 A window stand comprising a main working surface, a pair of inwardly inclined supports secured to and depending from the outer end of said surface, struts secured to said working surface and said supports, and
- 10 gripping means secured to the opposite end of said working surface, said gripping means adapted to sustain the main working sur-

face in horizontal position, transverse strips secured to the supports and the struts and extending beyond the sides thereof and steps 15 secured to and arranged transversely of the extended portions of said strips.

In testimony whereof I affix my signature in presence of two witnesses.

FREDERICK ROTTI.
